[57] CLAIM

The ornamental design for a light string storage device, as shown.

DESCRIPTION

FIG. 1 is a perspective view showing my new design of a light string storage device;

FIG. 2 is a side elevational view thereof with the opposite side being a mirror image thereof;

FIG. 3 is a front elevational view thereof with the rear view being a mirror image thereof;

FIG. 4 is a top view thereof;

FIG. 5 is a bottom plan view thereof;

FIG. 6 is a perspective view of a second embodiment of the design shown in FIG. 1;

FIG. 7 is a side elevational view thereof with the opposite side being a mirror image thereof; and,

FIG. 8 is a front elevational view with the rear view being a mirror image thereof.

The undisclosed top and bottom plan views of the second embodiment are identical to the same views shown in the first embodiment.
